UNITED STATES PATENT OFFICE.

GEORGE D. JONES, OF PETERSBURG, VIRGINIA.

IRONING-BOARD ATTACHMENT FOR WARDROBE TRUNKS.

Application filed May 2, 1923, Serial No. 636,150. Renewed March 5, 1926.

The invention relates to trunks and more particularly to convertible or wardrobe trunks of the character shown and described in co-pending application filed May 2, 1923, Serial No. 636,149, which are adapted to be placed upon end and which comprise a section in which articles of clothing may be suspended on hangers and a section containing a tier of drawers for receiving sun-dry articles.

The primary object of the invention is the provision of an ironing board which, when adjusted for service, is supported wholly by the trunk and which, when not in use, may be conveniently stored within the trunk so as to be out of the way and occupy little space.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application:

Figure 1 is a perspective view illustrating the application of the invention, the trunk being open and the ironing board in position for use, the full lines designating the wardrobe or clothes section and the dotted lines the section containing the tier of drawers,

Figure 2 is a vertical cross section of the wardrobe or clothes section of the trunk, the top being open and the full lines showing the ironing board stored within the trunk and the dotted lines illustrating the position of the ironing board when adjusted for use,

Figure 3 is a sectional detail showing more clearly the attaching and supporting means for the ironing board, and

Figure 4 is a detail perspective view of a portion of the attaching means of the ironing board.

Corresponding and like parts are referred to in the following description and designated in the several views of the drawings by like reference characters.

The trunk illustrated comprises a wardrobe or clothes section 1 having a hinged top 2 and a section 3 containing a tier of

drawers. The several parts may be of any finish and design common in the art.

The section 1 includes a removable shoe box 4 and the space above the shoe box is closed by means of a door 5 which forms a part of the section and rests upon the box 4 and is slidable in guides at the inner forward edges of the sides of the section 1. This door is of light structure and closes the open front of the section 1 and forms a support for the ironing board 6 when adjusted in position for service, as indicated most clearly in Figure 1 and by the dotted lines in Figure 2. No claim is made for the dust-door 5 in this application, as it is covered by my copending application Serial No. 636,149, filed May 2, 1923. A metal frame 7 is disposed at the top of the section 1 and is firmly attached thereto and serves as bracing and connecting means for the back and sides comprising the section. The frame 7 is riveted or otherwise secured to the upper portion of the back and sides comprising the section and supports rods 8 which are adapted to receive the hangers, not shown, upon which the articles of clothing are placed when in position in the section 1, as will be readily understood.

In accordance with the present invention, a bracket 9 is firmly attached at its lower end to the frame 7 and extends above the top of the section 1 so as to lie within the top 2 when the latter is closed. The upper end of the bracket 9 comprises a lateral extension 10. A threaded opening 11 is formed in the lateral extension 10 and a corresponding threaded opening 12 is formed in the frame 7 and the lower portion of the bracket 9 attached to the frame. The threaded openings 11 and 12 are adapted to receive a thumb screw 13 which is carried by the rear end of the ironing board 6 and which serves to secure the ironing board in either operative position, as indicated in Figures 1 and 3, or in inoperative position, as illustrated in Figure 2. An angle strip 14 is attached to the rear end of the ironing board 6 and reinforces and strengthens the same. The angle strip 14 has an opening 15 which is in line with a corresponding opening formed in the ironing board to receive the thumb screw 13. A notch 16 is formed in an edge of the angle strip 14 to receive the lateral extension 10 of the bracket, or the upright portion thereof, as shown most clearly by the

full and dotted lines in Figure 3. When the ironing board is placed in position for service, as indicated in Figure 1, it rests upon the door 5 and the lateral extension 10 of the bracket 9 and is prevented from displacement by means of a thumb screw 13 engaging the threaded opening 11 of the part 10. When the ironing board is not required for immediate service, it is conveniently stored 10 within the section 1 so as to occupy a position adjacent the back thereof so as to be out of the way and occupy a minimum amount of space. The projecting edge portion of the angle strip 14 engages and rests 15 upon the rear portion of the frame 7 and displacement of the ironing board is prevented by the thumb screw 13 engaging the threaded opening 12, as shown most clearly by the full lines in Figure 2 and the dotted 20 lines in Figure 3. In this position of the ironing board, the notch 16 in the projecting edge portion of the strip 14 receives the foot of the bracket 9.

What is claimed is:

- 25 1. In a wardrobe trunk having a clothes section having a hinged top, an ironing board adapted to be placed in storage position within the trunk when not required for service and adapted when adjusted for service to extend across the top of the clothes section and supported thereby, and means for rigidly securing the rear end of the ironing board to the clothes section in either of the two mentioned positions.
- 30 2. In a wardrobe trunk having a clothes section having a hinged top, a bracket at the top and rear of the clothes section, an ironing board adapted to be stored within the clothes section adjacent the back thereof or to be supported horizontally across the top of the clothes section, and means carried by the ironing board to secure the same to the bracket in either one of the two mentioned positions.
- 35 3. In a wardrobe trunk having a clothes section and a hinged top therefor, a bracket at the top and rear of the clothes section, an ironing board adapted to be stored within the clothes section adjacent the back thereof or to be supported across the top of said section, an angle strip applied to the rear end of the ironing board and having an edge portion projecting and notched to provide clearance for said bracket in either 40 position of the ironing board, and means
- 45 carried by the ironing board to engage the bracket and secure the ironing board in either one of the two mentioned positions.
- 50 4. In a wardrobe trunk having a clothes section open at the top and front and provided with a hinged top, a metal frame attached to the upper portion of the back and sides of the clothes section and serving to strengthen and reinforce the same, a bracket attached to said frame and having an inwardly disposed lateral extension, said lateral extension and the lower portion of the bracket each having a threaded opening, an ironing board, an angle strip attached to the rear end of the ironing board and having 55 a projecting edge portion in which is formed a notch to clear the bracket or the lateral extension thereof, according to whether the board be placed in operative position or inoperative position, a thumb screw applied to the ironing board and adapted to engage either the threaded opening of the lateral extension or the lower portion of said bracket, and means extending across the open front of the clothes section to help support 60 the ironing board in operative position.
- 65 5. In a wardrobe trunk having a clothes section having its upper and front portions open, a hinged top for closing the upper portion of the section, an ironing board adapted to be stored within the trunk when not required for use and to be placed across the top of the clothes section when adjusted for service, the rear end of the ironing board being supported by the back of the clothes section, a door supported within the front of the section and forming a support for the ironing board when in operative position, and means for securing the ironing board to the back of the clothes section to prevent 70 displacement thereof when in operative position.
- 75 6. In a wardrobe trunk embodying a clothes-section, an ironing-board adapted to be placed in storage position adjacent the back wall of said clothes-section within the trunk when not required for service and adapted when adjusted for service to extend across the top of the clothes-section and be supported thereby, and means for attaching the rear end of the ironing-board to the clothes-section in either of the two mentioned positions.

In testimony whereof I affix my signature.
GEORGE D. JONES.
